By their Attorney Hood & Boyd

UNITED STATES PATENT OFFICE.

FREDRIC C. WEIR AND HENRY B. FURNESS, OF CINCINNATI, OHIO; SAID FURNESS ASSIGNOR TO SAID WEIR.

FILTER.

SPECIFICATION forming part of Letters Patent No. 471,496, dated March 22, 1892.

Application filed September 14, 1891. Serial No. 405,677. (No model.)

To all whom it may concern:

Be it known that we, FREDRIC C. WEIR and HENRY B. FURNESS, citizens of the United States, and residents of Cincinnati, in the 5 county of Hamilton and State of Ohio, have invented certain new and useful Improvements in Filters, of which the following is a specification.

This invention relates to filters, and has for 10 its object to provide novel means for cleaning a filtering-cylinder.

To accomplish this object our invention involves the features of construction and the combination or arrangement of devices here- 15 inafter described and claimed, reference being made to the accompanying drawings, in which—

Figure 1 is a longitudinal central vertical section of our improvement. Fig. 2 is an end 20 view thereof. Fig. 3 is a modification of Fig. 2. Fig. 4 is another modification.

1 represents the filter-case, 2 a filtering-cylinder, and 3 a shaft on which the same is mounted, which is journaled in the stuffing- 25 boxes 4.

5 represents a cap forming a chamber to receive the filtered water.

6 represents a hollow in the shaft 3 for conveying water from the cylinder to the filter- 30 ing-chamber 5.

7 represents a solid bar or body of abrasive material, which may be formed of burnt clay, emery, or other similar material; or sand-paper may be used for this purpose. It is shown 35 supported by guide-lugs 8 on the filter-case.

9 represents elastic rings engaging round the abrasive piece and the shaft 3, so as to hold the same in contact with the cylinder, thereby securing forcible yet yielding contact 40 of the abrasive body with the outside of the cylinder, which scours or scrapes off the débris or impurities deposited thereon when the crank 10 is turned.

In Fig. 3 we have shown another modification, which consists in providing the outer filter-case with guides composed of a housing or cap 11, and between which guides the abrasive bar 7 projects. It is provided with weight 12 for holding it in contact with the 50 cylinder.

In Fig. 4 we have shown another modifica-

tion of spring which may be substituted in lieu of weight 12. 13 represents said spring, which is of elliptic form and which is secured to the abrasive bar by screw 14. 15 represents the inlet-pipe, and 16 the discharge-pipe for washing out the dirty water. 17 represents the discharge-pipe for discharging filtered water, the desideratum being to obtain a yielding engagement of the abrading-bar applied to the outer periphery of the cylinder. This yielding engagement may be either by weight or spring.

We have shown as the preferred form of construction the cylinder revolving against 65 the abrasive bar, which is held stationary by the outer casing. It is obvious that the rotary motion might be applied to the outer cylinder and the inner one held stationary, or other similar modifications made without departing from the principal feature of our invention.

It will be observed that the abrasive body projects outside of the cylinder in Fig. 3 and works in the guides and that suitable means 75 are provided to force the abrasive body against the periphery of the cylinder so as to clean off the deposit thereon. By making the guides outside of the cylinder a considerable saving of weight is effected and the abrasive 80 body is better held in place and more easily forced against the filter-cylinder than if the cylinder is made large enough to have the guides inside. We do not limit ourselves to the use of a solid bar of abrasive material. 85 Of course it is not absolutely essential that the abrasive or scraping material should be in exactly radial planes, but it should be, substantially, so that it can act as a scraper, and either weights or springs may be employed 90 to force the abrasive body against the periphery of the cylinder, so that the proper friction can be obtained.

Having described our invention, what we claim is—

1. The combination, with a filter-case and a filtering-cylinder arranged therein, of a solid bar of abrasive material extending substantially the full length of the filtering-cylinder and yieldingly held in contact with the external surface thereof, substantially as and for the purposes described.

2. The combination, with a filter-case, a rotary filtering-cylinder arranged therein, and means for turning the cylinder, of a solid body of abrasive material extending substantially the full length of the cylinder and yieldingly held in contact with the external surface thereof, substantially as described. 25
- 5 3. The combination, with a filter-case, a filtering-cylinder arranged therein, and radial guides, of an integral abrasive body extending radially out from the cylinder the full length thereof, supported by and movable in the guides and yieldingly held in contact with the external surface of the cylinder, substantially as described. 30
- 10 4. The combination of a filter-case provided with radial guides, a filtering - cylinder arranged in the filter-case, means for turning the cylinder, an integral abrasive body extending substantially the full length of the cylinder, supported by and movable in the guides and projecting radially therefrom, and means for holding the abrasive body yield- 35

- 35

ingly in contact with the external surface of the cylinder, substantially as described. 25

5. The combination, with the outer filter-case, the filtering - cylinder, and the radial abrasive material, of the housing or cap 11, secured to the outer case and serving as a guide to hold and direct the radial abrasive material in contact with the outer periphery of the filtering-cylinder, substantially as specified. 30

6. In combination with the filtering-cylinder 2, the abrasive material 7, supported upon the cylinder by guides formed upon the outer casing, and springs applied thereto forcibly holding it in engagement, substantially as specified. 35

In testimony whereof we have hereunto set our hands.

FREDRIC C. WEIR.
HENRY B. FURNESS.
